UNITED STATES PATENT OFFICE

JULIEN C. MILLER, OF PADUCAH, KENTUCKY

COLLAPSIBLE CRATE

Application filed May 9, 1929. Serial No. 361,615.

This invention relates to a collapsible crate designed primarily for use in holding berry baskets.

It is an object of the invention to provide a crate the greater portion of which is formed of thin sheets of veneer so assembled that when the crate is not in use, it can be laid out flat and a stack of crates easily transported at low cost.

Another object is to provide a crate of this character which is light in construction and, when set up for use, will hold superposed trays of baskets securely in position so that they will not become dislodged and the contents spilled while in transit.

A further object is to provide a crate having simple and efficient means for fastening it together while in use without requiring the use of staples, nails, or other fastening devices such as commonly employed and all of which tend to mutilate the crate and render it unfit for subsequent use.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed, without departing from the spirit of the invention.

In the accompanying drawings the preferred form of the invention has been shown.

In said drawings,

Figure 1 is a front elevation of the crate set up for use.

Figure 2 is an end elevation thereof.

Figure 3 is a vertical longitudinal section.

Figure 4 is a vertical transverse section.

Figure 5 is a perspective view of one of the articulated frame members of the crate.

Figure 6 is a perspective view of one of the end panels or heads.

Figure 7 is a perspective view of one of the trays used for holding the heads properly positioned when the crate is set up.

Figure 8 is a side elevation of the crate collapsed or folded.

Figure 9 is a plan view of a portion of the

preferred form of jointed frame used with the crate.

Figure 10 is a side elevation of the structure shown in Figure 9.

Figure 11 is a portion of another form of jointed frame.

Figure 12 is a plan view of a portion of another modified form of frame.

Referring to the figures by characters of reference, 1 designates the front section of a frame member provided at one end with a short tongue or ear 2 provided with an aperture 3 while its other end is forked to provide spaced ears 4. The bottom section of the jointed frame has been indicated at 5 and is provided at one end with a tongue or ear 6 while its other end is forked to provide spaced ears indicated at 7. Ear 6 is connected to ears 4 by a pivot pin 8 and ears 7 are connected by a pivot pin 9 to a tongue or ear 10 extending from the back section 11 of the jointed frame. This section, like the section 5, has spaced ears 12 connected by a pivot pin 13 to the top section 14. This section is similar in construction to the sections 11 and 5 and has a forked end providing ears 15 through which is extended an aperture 16.

In practice preferably two jointed frames such as described are used, one being located at each end of the crate. These frames are connected by strips 17 formed preferably of veneer and attached to the frames by stapling or in any other manner desired. Where these strips 17 are extended across the frame they are reinforced or backed by outer strips 18 arranged parallel with the respective sections of the frame and attached to the strips 17 and to the frame 5 by staples or other suitable fastening means.

The front, bottom, back, and top panels formed of the strips 17 and 18 and the frame sections can be reinforced by metal tie wires or strips 19 held thereto by staples or the like as shown and terminating adjacent the top edge of the front panel and the front edge of the top panel. This can be seen by referring particularly to Figure 2. These reinforcing or tie strips are so proportioned that, when the crate is set up for use, they will extend

taut across the joint between the panels as shown for example in Figure 2.

The frame members 1 located at the ends of the crate are provided with special fastening devices. Each of these consists of a resilient wire 20 extending longitudinally of the section 1 and held thereto by staples 21. A finger 22 is extended radially from one end of the wire while another finger 23 is extended radially from the other end thereof, the two fingers being disposed out of line. When finger 22 is resting flat against the side of section 1 the finger 23 is substantially in line with the opening 3. Obviously by pulling the finger 23 laterally away from section 1 and then placing the ears 15 at the sides of ear 2 with the openings 16 and 3 in alignment, finger 23 can be inserted through these alining openings and thus serve to hold the frame members 1 and 14 together.

In connection with the front, bottom, back, and top panels of the crate there are used end panels or heads 24. Each of these is formed of two or more thicknesses of veneer, the grain of each thickness being extended at an angle to the grain of the next adjoining thickness and the said thicknesses being held together by stitching. Each panel is cut to lap the sections 1, 5, 11, and 14 of the end frames 30 and to extend close to the inner faces of the strips 17 forming parts of the front, back, bottom, and top panels.

In using this crate the sectional frames are laid out flat so that the panels of which they form parts will also be flat. The baskets B are stacked on the bottom panel with trays interposed between the layers of baskets. As shown in Figure 7 each tray can consist of parallel strips 25 connected by cross strips 26 of veneer or the like. These trays are adapted to abut at their ends against the heads or end panels 24. After the proper number of baskets have been assembled upon the bottom panel of the crate the heads 24 are placed in upstanding positions against the ends of the interposed trays and the ends of the rows of baskets B following which the back, front, and top panels are brought to positions where the frame members of the ends therof will lap the edge portions of the heads 24 and the stacked baskets will be enclosed. The ends of the frame members 1 and 14 are then fastened together by the means heretofore described whereupon all of the parts will be held assembled securely.

To obtain access to the contents of the crate the fingers 23 are pulled out of engagement with the ears 15 and the top, front, and back panels are swung away from the stacked baskets which are thus left exposed and can be removed readily.

By laying out the panels so that they will lie flat with the trays 26 and heads 24 resting thereon, a number of the crates can be stacked

and thus shipped at low cost because of the relatively small space occupied thereby.

Instead of forming the frame members with forked ends and tongues as heretofore explained, each frame member can be provided with a pair of ears 27 at each end as shown in Figure 11 and said frame members can be kept at their points of connection as shown at 28. If preferred, however, each frame member can have a single ear 29 at each end, the ear at one end being adjacent one side while the ear at the other end is adjacent the other side. Thus when the frame members are assembled, as in Figure 12, they will occupy the same plane.

What is claimed is:

A collapsible crate including relatively movable panels, and means for detachably connecting the panels, each of said means including a resilient wire slidably and rotatably mounted on one of the panels and fingers radiating from the respective ends of the wire but in different planes, one of said fingers constituting means for limiting the rotation of the wire and the other finger constituting means for engaging the two panels to hold them against relative movement.

In testimony that I claim the foregoing as my own, I have hereto affixed my signature.
